GIBSON H. GOFF AND LEE ROLLINS, OF RODA, VIRGINIA, ASSIGNEES OF ONE-HALF TO
WILLIAM A. OWENS, OF RODA, VIRGINIA.

TROLLEY-WIRE SUPPORT.

1,184,573.

Specification of Letters Patent.

Patented May 23, 1916.

Application filed March 17, 1915. Serial No. 15,011.

To all whom it may concern:

Be it known that we, GIBSON H. GOFF and LEE ROLLINS, citizens of the United States, residing at Roda, in the county of Wise and State of Virginia, have invented certain new and useful Improvements in Trolley-Wire Supports; and we do hereby declare the following to be a full, clear, and exact description of the invention, such as will enable others skilled in the art to which it appertains to make and use the same.

This invention relates to new and useful improvements in trolley wire supports, and has for its principal object to provide a device which will easily and quickly clamp a trolley wire and hold the same firmly in place.

Another object of the invention is to provide a trolley wire support which is so constructed as to avoid engagement with the trolley wheel when the same is passing over the support.

A further object of the invention is to provide a novel means for tightening the support on the wire to prevent the wire from slipping from place.

Still another object of the invention is to provide a device which will prevent the wire from twisting or from becoming loosened on curves.

A still further object of the invention is to provide a novel means for tightening the clamp so that the wire may be firmly held in place and tightened from time to time.

With these and other objects in view, the invention consists in the novel combination and arrangement of parts which will be fully set forth in the following specification and accompanying drawings, in which,

Figure 1 is a view partly in section of a trolley wire support constructed in accordance with this invention, Fig. 2 is a sectional view taken at right angles to Fig. 1, Fig. 3 is a detail perspective view of the adjusting collar, Fig. 4 is a plan view of the wedge, and Fig. 5 is a fragmentary perspective view of the wrench used in connection with this device.

Referring to the drawings by characters of reference, the numeral 1 designates the main supporting body which is provided near its upper end with suitable screw threads 2. A central threaded axial bore 3 is formed in the supporting body 1 and this body is bifurcated at its lower end to form

a pair of downwardly extending projections 4 having formed thereon the ears 5. These ears are provided with suitable apertures for the reception of the pivot pins 6 by which the jaw members designated generally 60 by the numeral 7, are pivotally held in place. The jaw members, hereinbefore referred to, comprise the jaws 8 and the operating levers 9, intermediate which are suitable offset portions, through which the pivot pins 65 6 extend. The levers 9 are provided at their upper ends with the cam faces 10, in connection with which the wedge member, illustrated in Fig. 4 coöperates.

The wedge member hereinbefore referred to, is designated generally by the numeral 11 and comprises the body 12 which is formed with a central opening 13 and is provided at each end with the cam faces 14, which coöperate with the cam faces 10 of 75 the levers 9 in clamping the trolley wire. A suitable groove 15 is formed in the body 12 and is arranged to receive the pin 16 carried by the body 1 so that the wedge member will be prevented from turning when in 80 place.

Coöperating with the screw threaded portion 2 of the supporting member 1 is the adjuster designated generally by the numeral 17, which comprises the body 18 having formed thereon the flanges 19 and 20, each of which is provided with the diametrically opposed notches 21 which are arranged in alinement to receive the lugs on the wrench which will be more fully hereinafter described. The body 18 is formed with a centrally screw threaded aperture 22 which receives the threaded end 2 of the supporting member 1. It will thus be seen that as the adjuster is screwed down against the 90 wedge member 11, the jaws 8 of the jaw members 7 will be more firmly forced toward each other and a tighter grip on the trolley wire will be taken.

In order to move the adjusting screw the 100 wrench, best illustrated in Fig. 5, is provided which comprises the handle 23 having formed at one end the head designated generally by the numeral 24. This head comprises the arm 25 which is relatively long 105 and outwardly curved at its end as at 26, and the arm 27 which is relatively short and provided near its end with the lugs 28 which are disposed on opposite sides. These lugs 28 are arranged to engage in the notches 21, 110

while the arm 25 of the wrench head lies between the flanges 19 and 20. It will thus be seen that when the wrench is turned in the direction so that pull is exerted on the lugs, the adjuster is turned in the direction of the pull. In event it is desirable to change the position of the wrench, the reverse motion is given and it will be evident that the lugs 28 will ride out of their respective notches and be pushed around until they engage in the adjacent notches, and upon reversing the movement it will be evident that a fresh grip will be taken.

From the foregoing it will be evident that 15 a particularly simple and efficient clamp for the trolley wire is provided which will effectively grip the wire and hold the same against accidental movement and which, in case the wire should become loosened, may 20 be easily and quickly tightened.

While in the foregoing there has been shown and described the preferred embodiment of this invention, it is to be understood that such changes may be made in the combination and arrangement of parts as will fall within the spirit and scope of the invention as claimed.

What is claimed is:

1. A trolley wire support of the class described comprising a body member being exteriorly screw threaded and provided at its upper end with an interior bore, the lower end of said body member being bifurcated forming a pair of arms, said arms 35 having apertures therethrough, a stop lug formed on said body, a wedge slidably mounted on said body provided with a vertical groove in its inner wall adapted to engage the stop lug formed on the body to 40 prevent the rotation of the same, a pair of jaws pivoted on opposite sides of said body and between the arms, the upper ends of said jaws engaging the outer surfaces of the wedge forcing the same outwardly and 45 their inner end toward one another for firmly gripping a wire therebetween and means for engaging the exterior threads of the body and the wedge to prevent upward movement of the same.

50 2. A trolley wire support of the class described comprising a body, said body provided with exterior screw threads at its upper end, a bore formed in the upper end of said body, the lower end of said body being 55 bifurcated forming a pair of arms, said arms provided with apertures in opposite corners, a stop lug formed centrally in one

wall of said body and projecting outwardly therefrom, a pair of jaws, said jaws comprising a lever portion and a clamping portion 60 formed on one end of the lever portion, a projection formed centrally on said lever portion, said projection provided with apertures to align with the apertures of the ears formed on the arms, and means for pivotally holding the projections of the jaws between the arms, a wedge provided with cam faces slidably mounted on said body, said wedge provided with an interior vertical groove, said groove adapted to engage the 70 lug on the body when positioned thereupon to prevent rotation of the same, and a circular adjusting member provided with interior screw threads adapted to engage the exterior screw threads of the body and force 75 the wedge members down between the levers for forcing the same outwardly and their clamping ends inwardly for supporting a wire therebetween and hold the wedge against upward movement. 80

3. A wire support of the class described comprising a circular body having a bore formed in its upper end, said circular body being screw threaded exteriorly and interiorly, a stop lug formed centrally on one 85 wall of said body and projecting outwardly therefrom, the lower end of said body being bifurcated forming a pair of substantially rectangular arms, levers pivotally connected between the arms, said levers provided at 90 their lower ends with clamping members, a wedge, said wedge provided with a groove adapted to slidably engage the body, said groove engaging the stop lug for preventing the rotation of the same upon the body, 95 the outer faces of said wedge engaging the inner faces of the levers forcing the same outwardly, an adjuster, said adjuster comprising a body, angular flanges formed on opposite ends of said body, said flanges provided with a plurality of opposed notches, 100 said second mentioned body provided with interior screw threads, being screw threaded down over the screw threads of the first mentioned body to prevent the upward 105 movement of the wedge member.

In testimony whereof we affix our signatures in presence of two witnesses.

GIBSON H. GOFF.
LEE ^{his} X ROLLINS.
